UNITED STATES PATENT OFFICE

ARTHUR WURDACK, OF NORMANDY, MISSOURI

COMBINATION FRUIT PRESS AND STRAINER

Application filed January 31, 1929. Serial No. 336,342.

This invention relates to a combination fruit press and strainer and consists of the novel construction hereinafter disclosed.

An object of the invention is to provide an apparatus for pressing out the juice from fruit pulp and for straining the same, including means for agitating the body of pulp placed in the apparatus.

Another object of the invention is to provide a device of the class described including a cylinder having a reticulated bottom, an agitator adapted to rotate in the bottom equipped with radially movable blades for pressing the material in the cylinder against the reticulated bottom, said agitator also being provided with oppositely arranged agitators for distributing the body of the material in the cylinder substantially equally and to agitate or stir the body material constantly throughout the operation of the apparatus.

These objects, as well as others, will be apparent from the foregoing description reference being made to the accompanying drawings in which

Fig. 1 is a plan view,

Fig. 2 is a front elevation, a portion being broken away to illustrate the reticulated bottom of the agitating cylinder,

Fig. 3 is an end view,

Fig. 4 is a plan view with the upper portion of the agitating cylinder removed,

Fig. 5 is a vertical section,

Fig. 6 is a transverse section, and

Fig. 7 is a detailed view illustrating the mounting of the agitator blades.

In the embodiment of the invention illustrated in the drawings the device is shown as including a rectangular frame 1 supported by legs 2 to hold the frame in an elevated position above a horizontal support upon which the apparatus may be mounted. An apron 3 is preferably attached below the frame and against the inner face of the legs 2 at each end of the apparatus to prevent outward splashing of the juice or material passing from the cylinder of the apparatus. If desired, spaced strips 4 may be attached to the inner face of the aprons 3 said strips forming a channel in between to provide a

support for a removable leaf 5 that inclines inwardly toward the center of the apparatus to deflect the material passing from the cylinder. Extending below the frame 1 and attached thereto is a semi-cylindrical reticulated wall 6 which forms the bottom of the agitating cylinder. At each end of the reticulated wall are vertical end walls 7 attached to the inner face of the legs and forming, with the reticulated wall 6, the lower portion of the agitating cylinder. The upper portion of the agitating cylinder is formed from a rectangular frame 8 that fits upon the upper surface of the frame 1 and is connected thereto by hooks 9 or other connecting devices, hinges being used on one side and a hook on the other if desired.

A semi-cylindrical imperforate wall 10 is connected to the frame 8 and at each end of the wall 10 is a semi-circular imperforate wall 11 so that when the frames are together a complete cylindrical container having an imperforate upper wall and end walls and a reticulated bottom wall is formed.

The agitator comprises a central shaft 12 that is of a length sufficient to extend beyond the ends of the agitating cylinder when the agitator is mounted therein.

Journals are formed for the shaft 12 by providing semicircular notches 13 in the adjacent edges of the walls 7 and 11 so that when the upper portion of the cylinder is removed the agitator may be readily lifted from its mounting and when the two walls 1 and 8 are together the shaft 12 will be held in position for rotation.

The shaft 12 is provided at one end with a crank 14 for manual operation. It, of course, may be driven by any other suitable source of power if desired.

The shaft 12 carries a pair of spaced circular discs 15 which discs are connected with the shaft 12 by any suitable form of connection such, for example, as the keys 16 so that the discs rotate with the shaft. The discs are spaced so that the outer faces thereof are adjacent to the end walls of the agitating cylinder and are rigidly held in adjustment by transverse tie rods 17 connected at their opposite ends into the body of the discs 15.

The discs are equipped with leaves forming paddles, said leaves are formed from elongated rectangular members 18 which have a length corresponding substantially to the distance between the inner faces of the discs 15.

At each end of the member 18 are plates 19 attached to one face of the members 18 and extending beyond the respective ends thereof, and said plates seat in radial slots 20 extending inwardly from the periphery of the discs 15 and are retained in position by retaining plates 21 attached over the ends of the slots. The depth of the slots 20 is slightly in excess of the width of the plates 19 which permit a radial movement of the leaves or paddles.

Strips 22 of flexible material are attached to the members 18 adjacent to their outer longitudinal edges, said strips forming wipers. The leaves are preferably arranged in pairs diametrically opposite each other and a single pair has been found to be satisfactory in practice although the number may be increased if desired.

Between the members 18 are strips 23, said strips being disposed between the inner faces of the discs 15 opposite to each other and inclined in opposite directions. The strips are mounted so that the narrow edge thereof is at the periphery of the agitator and the wider face extends inwardly toward the center. These strips constitute distributors for moving the body of the material back and forth across the periphery of the agitator so as to equalize the material across the face of the reticulated bottom in advance of the leaves carrying the wipers.

By rotating the agitator the body of the material in the cylinder is thoroughly agitated and the juice and small particles that may pass through the openings in the reticulated bottom of the agitator are forced therethrough and accumulated in the container placed below the apparatus.

After the apparatus has been operated sufficiently to force from the body of the material all of the component thereof that will pass through the reticulated bottom, the upper segment of the cylinder is removed and the accumulated mass of material that does not pass through the bottom is removed.

From the foregoing it will be understood that the apparatus provides an extremely efficient machine for treating fruit pulp to separate from the fiber and other component of the material all of the juice and small particles, and that throughout the operation of the device clogging of the material is avoided by the equal distribution thereof resulting from the construction of the agitator. The relative movement of the members 18 radially in respect of the periphery of the agitator permits free rotation of the agitator and constitutes a highly efficient means of squeezing out the small particles of the material and forcing it through the bottom.

I am aware that the invention may be modified in certain particulars without departing from the nature, principle and scope thereof. I do not limit myself, therefore, to the exact details shown and described but what I claim and desire to secure by Letters Patent is:

1. An apparatus of the class described, an agitating cylinder having imperforate end and top walls and a reticulated bottom wall, a revoluble shaft extending through said chamber and outwardly through the end walls thereof, a handle for operating said shaft, an agitator carried by said shaft, including end discs, wiper blades mounted in said discs, and oppositely extending agitator and distributing blades arranged within the periphery of said discs and between said wiper blades.

2. An apparatus of the class described comprising a cylindrical container having an imperforate upper wall and a reticulated bottom wall, an agitator mounted in said container and adapted to rotate therein, said agitator being provided with a plurality of radially moving cross members and a flexible strip mounted on the outer edge of each of said cross members for engagement with the cylindrical wall and oppositely extending agitating and distributing plates located between said cross members.
